SYNCHRONIZING SYSTEM

Maurice Kenyon Taylor and Sidney Atkinson,
Hollinwood, England, assignors to Ferranti
Electric Inc., New York, N. Y.

Application April 18, 1935, Serial No. 17,088
In Great Britain April 24, 1934

3 Claims. (Cl. 178—69.5)

This invention relates to synchronizing systems wherein a rotating body forming part of optical picture reconstituting apparatus in mechanically scanned television receivers is required to be maintained at a substantially constant angular velocity with respect to the frequency of an external electrical timing wave.

In most systems for attaining the above object, a synchronizing motor is employed, the use of which may, however, lead to the setting up of angular oscillations superimposed on the synchronous speed by reason of the synchronizing couple and the inertia of the body which is being synchronized; under these conditions the rotating body is said to be "hunting".

The main object of the present invention is to provide means in connection with the reception of television signals, whereby optical means for locating the position of the final image are controlled irrespective of any hunting of the rotor of the scanning device.

Referring to the accompanying diagrammatic drawing:—

Figure 1 illustrates part of a television receiver embodying the present invention, and

Figure 2 is a circuit diagram illustrating a convenient arrangement of mixing circuit.

In carrying the invention into effect according to one convenient form as illustrated in Figure 30 1, we provide an amplifier device 3 having a pair of input terminals 25, 25 and two pairs 26, 26 and 27, 27 of output terminals, the input terminals 25, 25 being connected respectively to an aerial 1 and an earth lead 2 whilst one pair 26, 26 35 of output terminals is connected to a light modulation circuit (not shown), as is customary; finally, the other pair 27, 27 of output terminals is connected to the ends of an electromagnet coil 4. This electromagnet coil is mounted on a core 40 5 having pole-pieces 28, 28 associated with a rotor 6 having a notched periphery forming teeth.

The magnet is conveniently of the form described in British specification No. 31,964 of 1933. 45 Also co-operating with the toothed disc 6 is a wave generator comprising a permanent magnet 8 having two pole pieces 7, 7, each carrying a coil 11, 11, the permanent magnet being mounted on an arcuate bracket 13 sliding on pins 14, 14 and capable of being moved by a pinion 15 engaging a curved rack embodied in the bracket.

The output from the coils 11, 11 is led to one pair of input terminals 9, 9, of a mixing circuit 55 16, and from another pair of input terminals

10, 10 leads 17 are taken to the ends of the electromagnet coil first mentioned above.

The mixing circuit conveniently comprises a pentode valve 33 the two control grids 34, 35 of which are associated respectively with resistances 36, 37.

The resistance 36 is connected to terminals 10 by way of a condenser 38 and the resistance 37 is connected to terminals 9 by way of a condenser 39, the connection to the grids being variable to 10 enable the voltages applied to the grids to be equalized.

The cathode is connected to one of the terminals 29 and the anode is connected by way of a battery 40 to the other terminal 29.

The output terminals 29, 29 of this circuit are connected, if desired by way of an amplifier, to a coil 18 mounted in the air gaps between three magnet pole pieces 19, 20, 21 of which 19 and 21 are caused to assume opposite fixed polarity. 20 The coil 18 is carried on a shaft 22, two hair springs 23 and 24 being provided to urge the coil into a predetermined plane. The terminals 29 convey current to and from the coil 18 by way of the hair springs. Mounted also upon the 25 shaft 22 is a mirror 30 so disposed as to reflect modulated light on to a screen 32 after being reflected by a mirror screw device 23^a and after passing through an object lens 31.

The mirror-screw 23^a is rigidly carried on the 30 spindle 24 which also supports rigidly the disc 6.

In operation, the incoming synchronizing signals in the aerial-earth circuit 1, 2 ultimately cause the electromagnet 4 to tend to maintain the notched disc 6 in step with them. By virtue 35 of the movement of the notched disc across the magnetic path of the wave generator, an alternating E. M. F. is generated whose frequency is directly proportional at all times to the instantaneous speed of rotation of the disc. This alternating E. M. F. is mixed in the circuit 16 with part of the amplified incoming synchronizing signal and on rectification produces a direct E. M. F. whose amplitude varies with the phase difference between the synchronizing wave from 45 the amplifier 3 and the E. M. F. produced by the wave generator 7.

The direct E. M. F. so produced, with or without amplification, is applied to the coil 18 and thus the position of the light on the screen 32 50 is varied in accordance with the phase displacement between the incoming synchronizing wave and that generated in the coils 11, 11 of the wave generator.

Adjustment of the phase angle may be per- 55

formed by adjustment of the position of the ar-
cuate bracket.

If desired the toothed wheel 6 may be mounted
5 on a spindle geared to a further spindle carrying
a mirror screw or drum.

According to a modification, the toothed disc
6 is spring mounted and the poles 28 are rigid
10 with the core 5, the wave generator pole pieces
cooperating with a further toothed disc mounted
rigidly on a shaft carrying the mirror screw 23a.

With this modification resilience of the mount-
ing of the pole shoes 28 is thus transferred to
that of the disc 6, a separate disc rigid with the
15 shaft carrying the mirror screw 23a co-operating
with the pole pieces 7, 7.

In a further modification the rotating scan-
ning body being synchronized may be geared to
the toothed disc instead of being rigid therewith.

The means for varying the angle of the wave
20 generator may be modified in any convenient
manner.

In a further modification of the mixing portion
25 of the system, the leads 17 from the am-
plifier 3 to the input terminals 10, 10 of the mixer
circuit 16 and/or the leads from the wave gen-
erator to the input terminals 9, 9 of the mixer
30 circuit are fed by way of suitable couplings, e. g.,
transformers, resistance-capacity couplings, etc.,
to a series circuit comprising the two inputs, a
rectifier and a resistance load which may be
shunted by a condenser.

Having now described our invention, what we
claim as new and desire to secure by Letters Pat-
ent is:—

35 1. A method of image framing in television
which consists in controlling the direction of
part of the path of a modulated light beam by
applying synchronizing impulses to a mixing cir-

cuit and to a synchronous motor, causing said
synchronous motor to drive a scanning device
and a wave generator the voltage wave gener-
5 ated by said voltage generator corresponds with
the instantaneous angular velocity of the scan-
ning device, applying said voltage wave to said
mixing circuit to produce a resultant varying
electrical output and applying said resultant
electrical output to modulated light beam de-
flecting device other than that used for scan-
ning.

2. A synchronizing system having means for
controlling the direction of part of the path of a
modulated light beam including a synchro-
nous motor, a mechanical scanning device, a 15
driving connection between said synchronous mo-
tor and said mechanical scanning device, a wave
generator in rigid association with said scan-
ning device, a mixing circuit, means for apply-
ing the output from said wave generator to said 20
mixing circuit, means for applying incoming syn-
chronizing impulses to said synchronous motor
and to said mixing circuit, additional means for
deflecting said modulated light beam, means for
deflecting said additional means, and means for 25
applying the resultant output from said mixing
circuit to said deflecting means to deflect said
additional means in accordance with the am-
plitude of the said resultant output whereby the
position of the final image is located irrespecti- 30
ve of any hunting of the scanning device.

3. A synchronizing system as claimed in claim
2 wherein said additional means comprises a
movable mirror interposed in the modulated
light beam and said deflecting means comprises 35
a moving coil rigid with said mirror.
